METHOD AND APPARATUS FOR
DEODORIZING OILS

Alton E. Bailey, Louisville, Ky., assignor, by mesne assignments, to National Cylinder Gas Company, Chicago, Ill., a corporation of Delaware

Application October 16, 1948, Serial No. 54,967

19 Claims. (Cl. 260—428)

1

This invention relates to treatment of fatty oils and fats. More specifically, the invention is concerned with novel equipment and also with a novel method for effecting deodorization of fatty oils and fats.

The invention is of especial importance in connection with the treatment of oils and fats to be employed in edible food products. It is highly desirable in the case of such edible products that the oil or fat employed be substantially free of objectionable odors.

With the foregoing in mind, it is a general object or purpose of the invention to increase the effectiveness of deodorization and thereby improve the quality of oils and fats to be employed in food products.

The invention is applicable to quite a wide variety of oils and fats, for instance cotton seed oil, soya bean oil, and lard. Various of such materials are commonly used in the preparation of food products such as salad dressing, margarine, etc.

Fatty oils and fats behave similarly with respect to deodorization treatment. The fats and oils are esters having certain chemical similarities which need not be considered in detail herein and, moreover, the fats, though more or less solid at room temperature are oily liquids at the temperatures employed for deodorization. For convenience all such materials are herein referred to as oils or fatty oils.

It is well known that various of these oils in their more or less crude state contain small percentages of certain constituents which impart to the oil an objectionable odor; and a number of processes have been developed for effecting deodorization of such oils.

In the deodorization techniques already known, it has been common to utilize heat, reduced pressure and stripping steam. In a typical prior treatment a batch of oil is heated in a simple tank having a vacuum connection at the top, while introducing stripping steam into the body of the oil.

An important object of the present invention is to greatly increase the efficiency of the stripping action of the steam, as compared with prior techniques.

A further object of the invention is to increase the efficiency of the treatment with reference to drawing the vacuum desirably established in the treatment equipment.

A further object of the invention relates to improvements in the structure of deodorization equipment.

2

The above and many other objects and advantages can best be understood following a description of the equipment used and further reference is therefore made herebelow to such objects and advantages.

The drawings illustrate a preferred form of equipment and in these drawings—

Figure 1 is a schematic view of an oil deodorization system constructed according to the present invention;

Figure 2 is a vertical sectional view of a treatment column incorporating improvements of the invention;

Figure 3 is an enlarged plan view of certain baffles used in association with oil treatment trays according to the invention, this view being taken as indicated by the line 3—3 on Figure 4.

Figure 4 is a vertical sectional view taken as indicated by the line 4—4 on Figure 3, illustrating the upper portion of an oil treatment tray and baffles associated therewith;

Figure 5 is a fragmentary horizontal sectional view through a part of the shell of the treatment column shown in Figure 2, showing certain parts in plan outline; and

Figure 6 is a fragmentary view taken as indicated by the line 6—6 on Figure 5.

In accordance with the present invention, the oil to be treated is successively delivered to a series of treatment zones defined by superimposed trays mounted within the treatment column. A given batch of oil is retained in each treatment zone for a predetermined time interval and is thereafter delivered to the next treatment zone where it is again retained for the same time interval. Following the treatment in the second zone the batch is delivered to a third treatment zone, and so forth, throughout the series. In addition, as soon as one batch has been discharged from the first treatment zone, a new batch is introduced into the first zone, so that all zones of treatment are in concurrent operation, the batch in each zone being of the same size and being treated for the same period of time.

In the preferred form of equipment, as fully described herebelow, there are five treatment zones through which each batch of oil is delivered, the respective treatments effected in each of these five zones being: first, heating of the oil to a temperature below effective deodorization temperature, with accompanying deaeration of the oil; second, further heating of the oil to effective deodorization temperature; third, deodorization by steam stripping; fourth, deodorization by steam stripping; and fifth, cooling.

With the foregoing brief description in mind, attention is now directed to the schematic view of Figure 1. As there seen oil is delivered from a supply A to a measuring tank B and from there to the several zones of treatment within the treatment column C. From the bottom of the column the oil is discharged into a drop tank or storage vessel D. If desired, the oil may then be delivered to a point of use through a filter E.

Reduced pressure is maintained within the column C by means of a steam jet ejector system F having a connection F' with the column C near the top thereof. The ejector system for pressure reduction within the column C may be of known type and the details thereof need not be considered herein.

The regions of the several treatment zones within the column C are indicated by the brackets numbered 1 to 5 inclusive, in Figure 1. Stripping steam is adapted to be introduced into each of the treatment zones from a steam supply connection 6 having branches 7, 8, 9, 10 and 11 extended to perforated steam inlet pipes 12, 13, 14, 15 and 16. Zone 1 has heater coils 17 therein adapted to be heated by circulation of steam therethrough. Similarly, each of zones 2 and 4 is provided with heater coils, as shown at 20 and 21. These heater coils are adapted to the circulation of a heat exchange medium, for instance the vapor of a eutectic mixture of diphenyl and diphenyl oxide. This heating vapor may be supplied from the boiler G through a supply connection 22 having branches 23 and 24, the medium being returned to the boiler through pipes 25 and 26 and the return line 27.

Zone 5 is provided with a cooling coil 28 through which a cooling medium, such as water, may be circulated.

Condensate may be drained from the shell of column C through a valve drainage connection 31 delivering into a drainage tank 32.

Figures 2 to 5 illustrate various features of construction of the column C shown in Figure 1. This column comprises a shell 33 preferably of cylindrical form arranged with its axis vertically disposed. The column is closed at the top by a head member 34 and at the bottom the column has a downwardly dished closure wall 35 with which the drainage pipe 31 is associated.

The several zones of treatment within the column are defined by vertically superimposed trays indicated by arrows numbered 1 to 5 inclusive, corresponding to the numbering of the zones in Figure 1. These trays are all of similar construction and a full detailed description of each one will therefore be unnecessary. Consider for example the top tray, which appears in Figures 2, 3 and 4. This tray has a bottom wall 36 and four upright side walls 37, thereby forming a square tray as clearly appears in Figure 3. The side walls of this tray are spaced appreciably from the shell wall and the angled corners thereof project to points closely adjacent to the shell wall to receive support from brackets such as indicated in Figure 5 at 38.

Toward the top of the tray a system of baffles is provided, these being best shown in Figures 3 and 4. As there seen a multiplicity of baffle plates 18 and 19 are assembled in the pattern of open squares nested one within another, being interconnected in spaced relationship by spaced angle pieces 29, to provide a tortuous path for the escape of vapors from the tray. The baffle plates are further braced by straps 30 secured to the side walls of the tray and also to the center piece 30a

to which the innermost of the baffle plates 18a are secured. The outermost of the plates 18 are connected with the side walls of the tray by plates 19a. Plates 18b at the side walls of the tray complete the baffle system. In addition to the function of providing a tortuous path for escape of vapors from the tray, the baffle system further constitutes an effective means for breaking up or splattering the oil which is thrown upwardly against the baffles in the manner described hereinbelow, while at the same time preventing escape of oil particles from the tray. The splattering of the oil is of importance in enhancing the stripping efficiency of the steam, as will further appear.

Above the baffle system is a peaked hood 39 carrying a depending square skirt 40 projecting down to a level somewhat below the top edges of the tray walls 37 and cooperating therewith and 20 also with the baffle plates 18b to define a tortuous exit passage for vapors leaving the tray into the shell space surrounding the trays. In effect, the plates 18b (which project inwardly from the side walls of the tray) form a deflector ring underlying the skirt 40, which depends from the hood 39. Drainage ports are preferably provided through the plates 18b near the outer edges thereof for return of small amounts of oil which may work their way to the region above the plates 18b. The hood 39 is supported by straps 41 and the edges 25 of the hood advantageously project somewhat beyond the side walls of the tray so that any condensate which may drip from the edge of the hood will be delivered into the shell space, rather than into the interior of the tray.

A depressed corner portion 42 is provided at one top corner of each tray, being walled off from the baffle system, and this portion is apertured to 35 pass the oil inlet pipes for the several trays. 40 Thus, for the top tray the oil inlet pipe 43 (receiving oil from the measuring tank B) extends into the top tray through the peaked hood 39 and the corner portion 42. A typical batch of oil will be 45 of a size to fill the tray to the level indicated at L.

A drop or discharge valve 46 communicates with the bottom of tray 1 and provides for delivery of the batch of oil therefrom downwardly into tray 2 through the delivery pipe 47. Trays 2 to 5 inclusive are of essentially the same construction as that fully described above, each tray having bottom and side walls, hood and baffles, as is shown in Figure 2. Delivery of oil from tray 2 to tray 3 is effected by valve 48 and discharge pipe 49. Valve 50 and pipe 51 serve to deliver oil from tray 3 to tray 4. Oil is delivered from tray 4 to tray 5 by valve 52 and discharge pipe 53. At the bottom of tray 5 a discharge valve 54 is provided which controls the flow into the final discharge pipe 55 extending downwardly through a connection 56 passing through the bottom 35 of the shell. Pipe 55 serves to discharge the oil from tray 5 into the drop tank D (see Figure 1). Connection 56 with the drop tank provides for communication between the vacuum space of the shell and the drop tank D to thereby effect reduction of pressure in the drop tank.

Shell C is provided with a series of manholes each of which is located adjacent one of the valves 46, 48, 50, 52 and 54. The manholes are provided with covers 57, 58, 59, 60 and 61 which provide convenient access to the drop valves and also to other parts of the equipment located interiorly of the shell, especially in the regions between the vertically superimposed trays.

Further features of the tray arrangement in the

shell and of the arrangement of the drop valves between trays is shown in Figures 5 and 6. The general arrangement of parts is similar so that not all of them need be described. The showing of Figure 5 illustrates in plan the top of tray 2 and the drop valve 46 between tray 1 and tray 2. This figure shows that an appreciable space is provided within the shell around the trays. Figures 5 and 6 further show drop valve operating mechanism including flexibly jointed shafting 44 penetrating the shell wall 33 and connected with a valve operating motor 45 which may be mounted on the outside of the shell.

In a typical installation and operation thereof each tray has an oil capacity of 2500 pounds. A measured 2500 pound batch of oil, for instance cotton seed oil, is introduced from the measuring tank B into tray 1. The batch is held in tray 1 for a period of one-half hour, during which time it is heated by the coils 17 and is subjected to the stripping action of steam introduced through the perforated pipe 12. The steam ejector is of course placed in operation prior to introduction of any oil into the column and a low pressure is established within the column, for instance a pressure of 6 mm. Hg. Each tray is placed in communication with the vacuum zone of the shell through the baffled passages at the top, so that the reduced pressure is effective with reference to the interior of all trays.

In the typical treatment, the temperature is raised in tray 1 to about 320° F. Incidental to this increase in the temperature of the oil part way to effective deodorization temperature, the oil is deaerated, the air passing off with the stripping steam into the vacuum zone in the shell and finally out through the vacuum connection F'. At the conclusion of the half-hour treatment in tray 1, the batch of oil is delivered to tray 2 and is retained in tray 2 for an additional one-half hour period during which time it is subjected to the action of stripping steam, and the temperature is raised by the heater coil 20 to an appropriate value for deodorization, for instance 460° F. During this second one-half hour period, another batch is introduced into tray 1 and is treated as above described to increase the temperature of the oil to a point below effective deodorization temperature and to effect deaeration.

Following the second one-half hour period the batch in tray 2 is delivered to tray 3 and is held therein for a third treatment period of one-half hour, during which time deodorization is effected under the influence of stripping steam introduced through the perforated pipe 14. The drop valves are then again operated to effect delivery of the batch from tray 3 to tray 4, and to advance the batches in trays 1 and 2. In tray 4 the batch is retained for a fourth period of one-half hour, during which time it is further heated by the heater coil 21 so as to maintain this batch at an effective deodorization temperature. Stripping steam is also here introduced through the perforated pipe 15, and further deodorization takes place.

At the conclusion of the fourth one-half hour period the drop valves are operated to deliver the batch from tray 4 to tray 5, and also to advance the following batches. In tray 5 the batch is again retained for a period of one-half hour during which time it is subjected to the action of stripping steam introduced through pipes 16 and also the cooling action of the cooler coil 28. This cooling coil is adapted to drop the temperature

of the oil to about 130° F., so that upon discharge of the oil following the fifth one-half hour treatment period, the oil is at a temperature well below that at which any appreciable oxidation would occur. Upon discharge of the batch from tray 5 it mingles with the oil in the tank D and will be pumped therefrom to the filter E.

From the foregoing it will be seen that the sequence of treatments provided constitutes in effect a semi-continuous treatment, all phases of which are occurring concurrently, each batch of the oil being sequentially advanced through each treatment zone.

While the foregoing constitutes the description of the preferred form of my invention, it will be understood that various other arrangements of the trays may be used. Ordinarily it will be advantageous to employ two heating trays as described above, wherein the oil is heated with steam and thereafter with diphenyl and diphenyl oxide vapor, or other high temperature heating medium, as thereby the size and cost of the boiler for high temperature heating is minimized. However, alternatively, heating to effective deodorizing temperature may be effected wholly by means of the high temperature medium, without the use of heating steam, in one or more heating trays. Similarly, in some cases one of the deodorizing trays may be eliminated, although ordinarily optimum dimensions in the apparatus will be achieved with two trays. In the five-tray arrangement, the heater coils in tray 4 may not always be required, or, in some cases, it may be advantageous to provide heating coils in both trays 3 and 4. The preferred arrangement of heating coils in trays 3 and 4 will be dictated primarily by the temperatures required for different portions of the deodorization period.

The distribution of stripping steam to the different trays is not critical and good results may be obtained with a wide variety of steaming rates, provided that sufficient steam is injected into the deodorizing trays to provide the required removal of volatile odoriferous materials. However, for reasons of economy, it is preferable to inject the greater part of the total stripping steam into the deodorizing trays, providing the heating and cooling trays with only enough stripping steam to effectively deaerate the fresh oil and to agitate the oil sufficiently to give good heat transfer from the heating or cooling coils. For example, in the typical apparatus described in the foregoing, with a capacity of 5000 pounds of oil per hour, 75 pounds per hour of stripping steam may be injected into each of the deodorizing trays 3 and 4, as compared with 25 pounds per hour injected into each of the heating trays 1 and 2 and the cooling tray 5.

It will be understood that the temperatures employed in the several stages of treatment will necessarily vary according to the particular oil being treated and according to other factors, such as the degree of deodorization treatment necessary to substantially eliminate objectionable odors.

In considering various of the objects and advantages of the system as above described, attention is first called to the fact that vaporization or stripping efficiency is a factor of prime importance in the operation of any deodorization equipment or process. When the stripping steam is introduced into a body of oil under reduced pressure the steam bubbles expand and apparently absorb the constituents or odor bodies which it is desired to remove. When the steam is car-

ried away, such constituents are carried with it. Efficient operation therefore requires bringing all parts of the mass of the oil into contact with the stripping steam as rapidly and thoroughly as possible.

The equipment of the present invention is outstanding with reference to stripping efficiency. This is due in large part to the employment of the baffle or splash plates 18, 19, etc., which are located above but relatively close to the surface of the oil in each of the trays. The kinetic energy of the rapidly expanding bubbles of steam rising through the batch in each tray acts to lift masses of the oil and to violently splash the oil against the baffles, with the result that the oil is effectively splattered in relatively fine drops or masses, thereby greatly enhancing the access of the stripping steam to all parts of the oil in the tray.

It will be observed that the baffles are so arranged at the top of each tray that only very small quantities of the oil are carried above the baffles during treatment. The hood 39 and skirt 40 arranged over the top of each tray present a surface for catching and returning to the tray the small quantities of oil which escape through the baffles. Moreover, both the baffles and the skirt 40 (cooperating with the side walls of the tray) serve to define tortuous passages which prevents oil from escaping from the tray notwithstanding the violent splashing of the oil against the baffles.

The hood just mentioned also acts to prevent any volatile materials distilled from the oil which condense upon the shell or other relatively cold portions of the apparatus, from running back into the oil being deodorized. Any such condensate will ultimately drain downward within the shell and accumulate in the bottom of the shell, from which it may be withdrawn through the drainage pipe 31.

As a consequence of the efficient stripping obtained by splashing of oil against the baffle plates and the effective prevention of reflux of distilled material back into the oil, it has been found that the steam required for stripping is greatly reduced as compared with the well known batch deodorizer of the prior art. For example, only 4.5 pounds of stripping steam per 100 pounds of oil deodorized are required for many edible fat products, including hydrogenated cottonseed and soy bean oils, as compared with about 25 pounds ordinarily used in batch deodorization.

Since the oil treatment zones are substantially completely isolated within the trays and out of contact with the structure of the shell, it is possible to fabricate the shell of steel, even ordinary carbon steel, without adversely affecting the oil being treated. According to the invention, the trays, baffles and associated parts coming in contact with the oil are preferably fabricated of nickel or aluminum, since it has been found that these two metals are substantially inert with reference to their pro-oxidative effect on fatty oils and fats under deodorization conditions. In prior attempts to avoid adverse influence of metal-to-oil contact in deodorization equipment, it has been proposed to fabricate a treatment tank or shell of a metal such as nickel or aluminum, for the reason that in such prior equipment the arrangement of the treatment zone or zones was such as to bring the oil into contact with the shell, either at the side walls of the shell or by virtue of refluxing from the top of the shell, or both. This proposal, however, would result in a very expensive shell structure, particularly in view of the fact that a high vacuum must be main-

tained within the shell. An important feature of the present invention, therefore, is the fabrication of the shell of an inexpensive and strong metal, such as carbon steel, and the fabrication of the trays and associated parts of nickel or aluminum, the physical arrangement of the trays, baffles, etc., being such as to substantially eliminate contact of the oil being treated with any part of the shell structure. Fabrication of the trays from nickel or aluminum is not excessively costly particularly since the trays need not withstand a large pressure differential and therefore may be made of thin gauge sheeting.

Still another feature of great importance is the employment of trays having side walls spaced appreciably from the inside wall of the shell. This provides a vacuum space surrounding the trays and extending throughout the height of the column. Several important advantages follow from this arrangement. In the first place, the vacuum space surrounding the trays serves as heat insulation, thereby minimizing heat loss from the treatment trays through the shell wall, even in the absence of lagging applied to the exterior surfaces of the column. The vacuum space surrounding the trays and extending throughout the height of the column, together with the particular arrangement of trays provides independent communication of each tray with the vacuum space and thereby reduces pressure losses which would otherwise occur were the vacuum drawn serially through the oil in the several treatment zones. In this way, substantially the same low vacuum is maintained on the oil throughout the treatment period.

A further desirable feature of the vacuum space between the trays and the shell is that this method of construction renders it impossible for air, leaking accidentally into the shell, to pass through the oil in process of deodorization. It is well known that air leaking into the deodorizer and reacting with the hot oil therein, is a prime cause of trouble in the operation of batch deodorizers or other deodorizers of conventional construction.

It will be observed that the vacuum space surrounding the trays is provided by employment of trays which are square, rather than circular in horizontal section. This is of advantage for several reasons including the fact that the square or angular tray construction greatly simplifies the fabrication of the trays, baffles, etc. Moreover, with the trays and shell proportioned in the manner clearly appearing in Figures 3 and 5, the corners of the trays extend to positions adjacent the shell wall and this simplifies the problem of mounting the trays within the shell.

Still another advantage of the equipment disclosed is that a change in the stock of oil being treated need not necessarily result in intermixing of one stock with another. This is avoided since the oil is treated in batches which are advanced through successive treatment zones in a manner to handle such batches completely independently of each other, so that a change in the oil being treated may even be effected without interrupting the operation of the column. All that is required for this purpose is that when the last batch of one stock has been discharged from the last treatment zone, the first batch of the different oil be diverted to a separate storage or drop tank after it has been subjected to the treatment in the last treatment zone.

In operating the equipment disclosed herein, it is preferred to establish a pressure in the column at least as low as 10 mm. Hg. In zones 1 and 2

it is preferred to heat the oil at such a rate that upon leaving zone 2 the oil is at a temperature between 400° F. and 500° F. After the slight temperature drop which may occur in zone 3, the temperature is preferably brought back again to the desired temperature in the range between 400° F. and 500° F. by the heater in zone 4. The cooling in zone 5 preferably effects a temperature drop to a point below 150° F.

Because of the fact that the oil is preliminarily deaerated in zone 1 and further because of the fact that the oil is treated in all zones without coming in contact with metals which would adversely influence the oil, it is practicable to effect deodorization (principally in zones 3 and 4) at relatively high and therefore very effective deodorization temperatures. More rapid deodorization is therefore achieved.

In considering the nature of the treatment which occurs in each of the several zones, it should be noted that as the temperature approaches deodorization temperature in zone 2, some preliminary deodorization will also take place.

The processing of oil in the equipment herein disclosed will also serve to remove free fatty acids from the oil being treated, this being of great importance, particularly where the treated oil consists of a fat, such as lard, which does not require alkali refining to remove pigments or other impurities.

I claim:

1. Equipment for use in deodorizing fatty oils and fats comprising a shell having a vacuum connection, a series of vertically superimposed trays in the shell including a first or upper tray, a second or intermediate tray and a third or lower tray, normally closed connections from tray to tray having discharge valves providing for sequential delivery of a batch of oil introduced into the uppermost tray downwardly from tray to tray, each tray having communication with the vacuum space in the shell independently of other trays, a heater for a batch of oil in the first tray providing for heating of such batch to a temperature appreciably below deodorizing temperature, a heater for a batch of oil in the second tray providing for heating of such batch to deodorizing temperature, and an inlet for introducing stripping steam into a batch of oil in the third tray to effect appreciable deodorization of such batch in the lower tray.

2. A construction according to claim 1 and further including a fourth tray in the shell below said third tray, a cooler for cooling a batch of oil in the fourth tray, and a normally closed connection having a discharge valve for delivering a batch of deodorized oil from the third tray to the fourth tray.

3. A construction according to claim 1 and further including a fourth tray in the shell below said third tray also in communication with the vacuum space in the shell, a normally closed connection having a discharge valve for delivering a batch of oil from the third tray to the fourth tray, an inlet for introducing stripping steam into a batch of oil in the fourth tray to effect further deodorization of such batch in the fourth tray, and a heater in at least one of the third and fourth trays for maintaining deodorization temperature of the oil therein.

4. A construction according to claim 3 and further including a fifth tray in the shell below said fourth tray, a cooler for cooling a batch of oil in the fifth tray, and a normally closed con-

nexion having a discharge valve, for delivering a batch of deodorized oil from the fourth tray to the fifth tray.

5. A construction in accordance with claim 1 and further including a fourth tray in the shell below said third tray also in communication with the vacuum space in the shell, a normally closed connection having a discharge valve for delivering a batch of oil from the third tray to the fourth tray, an inlet for introducing stripping steam into a batch of oil in the fourth tray to effect further deodorization of such batch in the fourth tray, a fifth tray in the shell below said fourth tray, a cooler for cooling a batch of oil in the fifth tray, and a normally closed connection having a discharge valve, for delivering a batch of deodorized oil from the fourth tray to the fifth tray.

6. Equipment for use in deodorizing fatty oils and fats comprising a shell having a vacuum connection, a series of vertically superimposed trays in the shell, including an upper tray, an intermediate tray and a lower tray, normally closed connections from tray to tray having discharge valves providing for sequential delivery of oil from each tray to the next lower tray in the series, each tray having communication with the vacuum space in the shell independently of the other trays, a heater for a batch of oil in said upper tray providing for heating such batch to deodorizing temperature, a heater for a batch of oil in said intermediate tray providing for maintaining a batch of oil at deodorizing temperature, and a cooler for a batch of oil in said lower tray, each of said trays being provided with an inlet for introducing steam into the oil in said tray.

7. Equipment for use in deodorizing fatty oils and fats comprising a shell of circular horizontal section, a series of vertically superimposed trays in the shell each being of angular horizontal section and having superimposed angular corners adjacent the shell wall, oil discharge connections extended from tray to tray in said superimposed angular corners, valves in said connections, valve operating means providing for serial delivery of a batch of oil from tray to tray and normally closed access ports in the shell wall adjacent said connections.

8. Equipment for use in deodorizing fatty oils and fats, comprising a series of trays for the oil to be treated, a shell surrounding the trays in spaced relation thereto to provide shell space between the shell wall and the trays, in which construction any air leakage from the exterior of the shell to the interior thereof enters the shell space between the shell wall and the trays, the upper portion of each tray being open to the shell space to provide for the discharge of vapors therefrom into the shell space, and the shell having an offtake connection for evacuating the shell space and for withdrawing vapors and leakage air out of the shell space without contact with the oil in the trays, and steam supply means for introducing steam into the oil in at least certain trays of said series including a separate steam inlet in each such tray for the introduction of fresh steam into the oil in each such tray independently of the introduction of steam into other of such trays and without contamination with vapors withdrawn from other trays or with leakage air in the shell space.

9. A process for deodorizing fatty oils and fats in a treating column comprising a plurality of trays for the oil to be treated, and a shell surrounding the trays in spaced relation to provide

shell space between the shell wall and the trays, the upper portion of each tray being open to the shell space to provide for the discharge of vapors therefrom into the shell space, in which construction any air leakage from the exterior of the shell to the interior thereof enters the shell space between the shell wall and the trays, which process comprises heating the oil in certain of said trays, introducing fresh steam into the oil in each of said trays, and withdrawing the vapors from each tray through the shell space and discharging all of the withdrawn vapors, together with any leakage air, externally of the shell without recontact of said withdrawn vapors or contact of said air with the oil in any of the trays.

10. Equipment for use in deodorizing fatty oils and fats, comprising a plurality of vertically superimposed trays for the oil to be treated, a shell surrounding the trays in spaced relation thereto to provide shell space between the shell wall and the trays, each tray being upwardly open for discharge of vapors therefrom into the shell space, and each tray being provided with a normally closed oil discharge connection the inlet end of which communicates with the interior of the tray through the bottom thereof to provide for substantially complete discharge of all of the oil in the tray, the discharge connection for an upper tray being extended to deliver the oil therefrom to the next subjacent tray and the discharge connection for the lowermost tray being extended out of the shell, and the discharge connections having discharge valves providing for sequential delivery of a batch of oil initially introduced into the uppermost tray downwardly from one tray to another.

11. Equipment for use in deodorizing fatty oils and fats comprising a shell having a vacuum connection, a series of at least three trays in the shell each having side walls spaced from the shell wall to provide a vacuum zone at least in large part surrounding the trays, at least the second and third of said trays being provided with stripping steam inlets, each tray being upwardly open for discharge of vapors therefrom into the shell space, a heater in the first tray of said series for raising the temperature of the oil to effective deodorization temperature, an oil discharge connection for delivering a batch of oil from the first tray to the second tray and having its inlet end communicating with the interior of the first tray through the bottom thereof to provide for substantially complete discharge of all of the oil in the tray, a similarly arranged oil discharge connection extended between the second tray and the third tray, normally closed valves in said discharge connections, and valve operating means providing for serial delivery of a batch of heated oil from the first tray to the second tray for deodorization therein and thereafter from the second tray to the third tray for further deodorization therein.

12. Equipment for use in deodorizing fatty oils and fats comprising a shell of circular horizontal section having a vacuum connection, a series of vertically superimposed trays in the shell, each tray being of angular horizontal section with side walls spaced appreciably from the shell wall to provide a vacuum zone in the shell at least in large part surrounding the tray, each tray also having a normally closed connection in the bottom thereof providing for sequential delivery of oil from tray to tray, the angular corners of all the trays lying adjacent the shell wall, and tray supporting devices located at said corners and

10 connected with the shell for support of the trays within the shell.

13. Equipment for use in deodorizing fatty oils and fats comprising a shell defining a closed chamber and having a vacuum outlet connection for removing vapors from said chamber, a series of trays mounted within said chamber, each tray being adapted to contain a body of oil and having an outlet for vapors released from said body of oil, said trays also being spaced from said shell to provide a common vacuum space within the chamber for receiving vapors directly from the vapor outlets of all of said trays, a normally closed oil discharge connection for the last tray of said series extended outside said shell, normally closed oil discharge connections providing for gravity delivery of oil from each of the other trays in the series to the next tray in the series, and discharge valves in all of said discharge connections operable to provide for sequential delivery of a batch of oil, initially introduced into the first tray, from tray to tray in the series.

14. Equipment according to claim 13 and further comprising oil heating means including a heater in one tray connected to a source of relatively low temperature heating fluid and a heater in another tray connected to a source of relatively high temperature heating fluid, said heaters being operable to heat simultaneously batches of oil in said two trays.

15. Equipment for use in deodorizing fatty oils and fats comprising a shell defining a chamber and having a vacuum connection for the removal of vapors from said chamber, tray structure mounted within said chamber and having side walls spaced from said shell to define therewith a vapor space at least in large part surrounding said tray structure, said side walls also defining a tray space adapted to contain a body of oil, means for introducing gaseous medium into the body of oil in said tray structure below the surface of the oil, and fluid deflecting structure overlying said body of oil and operative to intercept dripping condensate and to deflect such condensate laterally of the tray structure into said surrounding vapor space, said tray space being in communication with said surrounding vapor space at an elevation above the level of said body of oil but below said deflecting structure to provide for flow of vapors from the tray space into the surrounding vapor space.

16. A construction according to claim 15 in which the condensate deflecting structure comprises a hood spaced above the tray structure and extended laterally beyond the side walls thereof.

17. A construction according to claim 15 and further including vapor deflecting means below the condensate deflecting structure defining a tortuous passage in the path of flow of vapors from the body of oil in the tray structure to the region of communication with the surrounding vapor space in the shell.

18. Equipment according to claim 15 and further including means in the region of vapor flow from the tray space into the surrounding vapor space providing a tortuous vapor flow path and comprising a vapor deflecting element extending downwardly from the region of the condensate deflecting structure, and a cooperating element projecting inwardly from the region of a side wall of the tray structure, said elements being spaced and relatively positioned to cooperate in establishing said tortuous flow path.

19. Equipment for use in deodorizing fatty oils

and fats comprising a shell having a vacuum connection, a series of oil treatment tray structures in the shell each having side walls spaced from the shell wall to provide shell space at least in large part surrounding the tray structures, means for introducing gaseous medium into the oil in at least one tray of the series, an oil supply connection penetrating the shell wall and providing for delivery of oil into the first tray of the series, connections within the shell from one tray to another in the series providing for gravity delivery of oil sequentially from tray to tray in the series, and an oil discharge connection penetrating the shell wall and providing for discharge of the oil from the last tray of the series, the tray structures having means overlying the oil therein and serving to intercept dripping condensate and to deflect such condensate laterally of the tray structures into the surrounding shell space, and each tray structure having lateral communication with said surrounding shell space at an elevation between the level of oil in said tray structure and the condensate deflection means to provide a lateral path of discharge of

5

vapors from the tray structure into the surrounding shell space.
